CLAIM

The ornamental design for a growing plant pole, as shown and described.

DESCRIPTION

FIG. 1 is a front elevational view of the growing plant pole showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view showing the growing plant pole in an extended position.

The dashed line representations of a pot as shown in FIG. 7 are for illustrative purposes only and do not form any part of the claimed design.

FIG. 1
